HOSE-SUPPORTING FOUNDATION
BLOOMER GARMENT

Ruth Fontaine Peck, Minneapolis, Minn., assignor to Winget Kickernick Company, Minneapolis, Minn., a corporation

Application January 13, 1936, Serial No. 58,902

3 Claims.

(Cl. 2-33)

My invention relates to hose-supporting foundation bloomer garments and has for its object to provide in combination with what is known as a foundation bloomer garment, that is a close-fitting bloomer garment adapted to cover the lower part of the body from the waist down, a series of hose supporters directly attached to the inside of the garment where they will be entirely concealed from view.

10 It is a further object of my invention to provide hose supporters preferably formed of a flat loop of supporting elastic ribbon which will lie flat along the inside of the material of the foundation bloomer so as to be invisible through the garment.

15 It is a further object of my invention to provide such hose supporters at the front and the back of the leg of the bloomer whereby the stockings will be supported front and back, which will give a particularly smooth and effective support 20 for the stockings and hold them in a manner to prevent any possibility of wrinkles, and to distribute strains equally through the different parts of the stocking.

25 The full objects and advantages of my invention will appear in connection with the detailed description thereof, and its various novel features are particularly pointed out in the claims.

In the drawing, illustrating an application of 30 my invention in one form—

Fig. 1 is a front view of a figure wearing a foundation bloomer garment having my invention formed therewith. Fig. 2 is an enlarged front view of a portion of said garment showing the relative positions of front and rear hose supporters, these elements being shown in part in dotted lines and in part by portions of the garment being broken away. Fig. 3 is a view of a portion of the leg of the foundation garment 35 with a part broken away showing the manner of attachment of one form of the hose supporter. Fig. 4 is a side section of a leg of the bloomer garment showing the position of front and rear hose supporting attachments similar to that 40 shown in Fig. 3.

45 The foundation garment 10 is a close-fitting bloomer garment preferably made of somewhat heavy and elastic material which closely fits the form of the wearer. It is provided with legs 11 which may be made longer or shorter as wearing requirements dictate. Upon the insides of the legs 11, as clearly shown in the different figures, the hose supporters 12, of standard make, are secured to the inside of the upper leg portion of 50 the foundation garment 10. As shown in Figs. 1, 55

3 and 4, this securing is effected in the following manner: A loop 13 of elastic ribbon is carried through the elongated slot 14 of flat retaining eye 15 of the hose supporter 12. This ribbon is doubled upon itself and carried angularly so that the ends diverge upwardly. And again it is doubled upon itself as indicated at 16 in Fig. 3, where it is sewed flat to the inside of leg 11. In this manner an adjustable yielding support for the hose supporter 12 is provided, which may adjust 10 itself laterally to support more perfectly all pulls or strains from the stocking.

Another form effecting the support for the hose supporter is illustrated in Fig. 2, wherein an elastic ribbon 17 of materially greater length is 15 sewed at 18 and 19, respectively, to the side portions of legs 11. The ribbon passes freely through the slot 14 in eye 15 of the hose supporter 12 as indicated in dotted lines at 20, Fig. 2. This 20 gives a greater degree of lateral adjustability than in the form shown in detail in Fig. 3, and also will lie flat on the inside of the leg of the foundation garment and be concealed thereby.

As shown in Fig. 2, the back hose supporter 15 may be secured by a straight loop of elastic ribbon, the portions lying one over the other and sewed together and to the inside of the leg 11, as indicated at 21 in Fig. 2.

The advantages of this construction are clearly indicated in the foregoing description. It eliminates entirely any separate hose supporter. It does away with the customary method of attaching hose supporters to the outside of foundation garments where they will be visible through the 35 more delicate type of outer wearing apparel. The hose supporters are not only invisible because beneath the fabric of the legs of the foundation garment, but are supported in such a manner as to effectively distribute the supporting strains 40 from the top of the stocking so that the stocking will be drawn smooth and held uniformly upon the lower portion of the leg with no tendency to undue strain in any particular region, and, consequently, with no tendency to produce runs 45 or other injuries in delicate stockings.

I claim:

1. A foundation bloomer garment embodying legs, and having a flat elastic ribbon sewed at its ends to the insides of the legs of the garment 50 so as to lie flat under the material of the garment and be concealed thereby, and forming a flat loop of said ribbon, and a hose-supporting element formed with an elongated eye through which said flat loop extends, said hose-supporting 55

element being freely slidale along the flat loop of said ribbon.

2. A foundation bloomer garment embodying legs, and having a flat elastic ribbon having its 5 ends separated and sewed as so separated to the insides of the legs of the garment so as to lie flat under the material of the garment and be concealed thereby and forming a flat loop of said ribbon with portions diverging from the center 10 thereof, and a hose-supporting element formed with an elongated eye through which said flat loop extends, said hose-supporting element being freely slidale along the flat loop of said ribbon.
3. A foundation bloomer garment embodying

legs, and having a flat elastic ribbon sewed at its ends to the front and back of the insides of the legs of the garments so as to lie flat under the material of the garment and be concealed thereby, and being of such length as to form a flat loop 5 of said ribbon having the portions thereof from said sewed ends hanging in a broad angle with a flat loop at the center, and a hose-supporting element formed with an elongated eye through which said flat loop extends, said hose-supporting element being freely slidale along the flat 10 loop of said ribbon.

RUTH FONTAINE PECK.
